PENCIL CASE

Alex Arthur Lobel and Max Loft, New York, N. Y.

Application August 6, 1930. Serial No. 473,307

3 Claims. (Cl. 120—23)

Our invention relates to a pencil case and has for its principal object the provision of a novel construction of this character for use by school children.

6 One of the objects of the invention is the provision of a case of the character described which embodies certain desired features of simplicity and practicability, and which is made in the form of a book for convenience in carrying it in 10 closed condition by hand or in a school-bag, or for resting it in open condition upon a table or desk where the pencils are to be used.

Another object of our invention is the provision of a book form case which will be neat and 15 attractive in appearance and which will afford a pleasing novelty for school children, the device combining features both of utility and amusement.

More particularly, the invention relates to a 20 two-section book form case, the main section being constructed to rest stable upon a surface and to contain pencils, erasers, pencil sharpeners, etc. The second section, constructed to form a lid for the main section, is so hinge-connected 25 to the main section that it can be supported in open condition thereon.

Other objects and aspects of our invention will appear hereinafter.

The invention consists in the improved pencil 30 case, and in the form, construction and relative arrangement of parts, as will be hereinafter more fully described and subsequently incorporated in the subjoining claims.

For a full understanding of our invention reference is to be had to the accompanying drawing, which forms a material part of this specification, and in which:

Figure 1 represents a top plan view of our pencil and game board case, this view showing 40 both the case itself and the game board in open condition;

Fig. 2 is a cross section, taken on the line 2—2 of Fig. 1, a part of the lid section being shown as broken away; and

Fig. 3 is an elevation and section on an enlarged scale, looking in the direction indicated by the arrows associated with line 3—3 of Fig. 2, but with the foldable part of the game board closed upon the lid section.

50 The preferred form of construction, as illustrated in the accompanying drawing, comprises a main section adapted to rest stable upon a surface such as a table or a desk and which consists of a bottom member 10, a rear side composed of a block 11 and outer auxiliary strip 12,

opposing ends 13, and a front end 14. A box-like section or container is thus produced, and the interior of the same is divided by a longitudinal partition 15 disposed between the opposing ends 13 into a chamber 16 for the storage 60 of pencils 17 or other articles for use in writing. The space between the partition 15 and front side 14 is divided by a cross piece 18 into a chamber 19 designed to contain the game pieces which are herein represented as comprising 65 checkers 20. For the chamber 19 we preferably provide a lid 21 which is connected by a flexible hings 22 to the partition 15. In the present embodiment, the lid 21 is supported by its hinge 22 and by the cross piece 18 at one end when it is 70 moved into closed position as shown in Fig. 2. For convenience in opening the lid a finger piece 23 is attached thereto. The open space at the right of the cross piece 18 may be utilized as a storage space for a pencil sharpener 24, a lead-holding case 25, and other articles including an eraser 26.

From an inspection of Figs. 1 and 2, it will be seen that in the construction shown, the bottom member 10 has a marginal portion 27 80 which projects well beyond the opposite ends 13 and the front side 14. A covering 28 of any suitable material, such as fabric, imitation leather or genuine leather, is applied to the underneath face of the bottom member 10 and 85 to the face of the rear auxiliary strip 12, such covering also continuing over the top of a head strip 29 mounted upon the block 11 so as to elevate the rear side of the section and provide thereby an elevated surface or platform whereon 90 to rest the lid or cover for the main section, as will presently appear. Attached to the outer edge portion of the covering 28 and extending upwardly across the outer edge of the marginal portion 27 and well above the same, is a flexible 95 tape 30 which is furnished all along its top edge with hookless fasteners 31 of a well-known type.

The lid or cover for the main box-like section is represented as comprising a main member 32 100 and an auxiliary overlying layer 33. The covering 28 is continued, as best shown in Fig. 2, from the head strip 29 over the main member 32 of the lid, said covering being pliable or flexible so as to bend at 34 in order to permit 105 the closing and opening movements of the lid. As herein represented, a flexible fabric hinge 35 connects the lid with the raised head strip 29, said fabric hinge being preferably provided with two portions 36 which are suitably ex- 110

tended into and joined to the said head strip 29. The overlying layer 33 is provided with a relatively large cut-away portion 37 in order to provide a recess or sunken area adapted to 5 receive therein a game board part 38 which is swingable on a hinge part 39 formed integral with the hinge 35. A piece of fabric or paper 40, having delineated thereon markings indicative of the game—in the present instance the markings representing the usual squares for the game of checkers—, is applied to the bottom of the recess or cut-away portion 37 and upon the surface of the game board part 38. A finger clip 42, attached by a pivot 43, is swingable into 10 position to engage the game board part 38 and secure the same in its position in the recess 37. When the lid is swung into open position, as shown in Fig. 2, it will be seen that it rests upon the raised head strip and that it projects well 15 beyond the rear side of the main section. In order that the lid will be maintained in a horizontal position when a game is to be played, we preferably embed within the lid along its marginal portion remote from the hinge 35, a strip 20 weight 44. When the lid is swung into closed position to rest upon the opposing ends 13 and the front side 14, the provision of the weight within the lid along the marginal edge portion remote from the hinge 35, insures a relatively 25 tight closing effect.

As herein represented, we may attach to the lid on the side thereof opposite to the checker square markings, a pad of plain paper 45. Preferably, the mode of detachably securing 30 the pad consists in providing it with a backing in the form of a projecting tongue 46 which is adapted to be entered into a pocket structure 47 formed in the thickened region 48 of the game board part for the purpose of receiving such pad. For cooperation with the 35 strip of hookless fasteners 31 connected to the main section as hereinbefore described, we provide upon the lid a strip of hookless fasteners 49, the carrying tape 50 of which is joined to 40 the covering 28 so as to extend across the outer edge of the lid. A runner slide 51 is associated with the two strips of hookless fasteners 31 and 45 49 for connecting and disconnecting the same in a manner that will be readily understood.

50 In use, assuming that the two strips of endless fasteners have been disconnected through the movement of the runner slide 51 in the proper direction, the lid section can be swung into the open position where it rests upon and 55 projects from the raised rear portion of the main section, where to be maintained in substantially horizontal position because of the weight incorporated within the lid. With the lid thus swung into open position, free access 60 may be had to the chambers of the main section. If it be desired to play a game, the game board part 38 is released through the disconnection therewith of the finger clip 42, and thereupon said game board part is swung forwardly until it assumes a position substantially horizontal with the lid as shown in Fig. 2. Any 65 suitable article may be placed upon the cover 21 for supporting the game board part 38 in a position in which it will be substantially horizontal 70 with the lid. In the present instance, the rubber eraser 26 is illustrated as being employed for such purpose. When it is desired to close the lid, the game board part is swung into its 75 position within the recess 37 and secured therein by the finger clip 42. Thereupon the lid is

80 moved into closed position upon the end members 13 and side member 14, thus bringing the strip of hookless fasteners 49 into proper relation with the strip of hookless fasteners 31 so that through the proper manipulation of the runner slide 51 the two strips can be secured together. The two sections when closed and secured together by means of the runner slide 85 comprise a book-like structure which can readily be carried by school children or stowed in their school-bags.

90 While we have illustrated and described the preferred form of construction for carrying our invention into effect, this is capable of variation and modification, without departing from the spirit of the invention. We, therefore, do not wish to be limited to the precise details of construction set forth, but desire to avail ourselves of such variations and modifications as come within the scope of the appended claims. 95

We claim—

1. A pencil case, comprising a container section for pencils and the like, a raised platform mounted on one transverse edge of the container, a foldable lid section hingedly attached at its 100 central portion to the platform on the container section for movement into closed and open position thereon, said platform acting as a base for part of the lid when opened, a covering joined to said sections and having free edges 105 adjacent the free edges of the respective sections, and cooperative interlocking means extending along the free edges of the covering, adapted to be engaged to secure the lid section closed upon the container section and to be disengaged to 110 permit opening of the lid section.

2. A pencil case, comprising a container section having a weighted transverse end forming one wall of the container, a marginal portion projecting from the base of said section 115 forming a continuous lateral and front extension contiguous with the opposite marginal edges of the section and the side opposite the weighted end thereof, a raised platform on the weighted end of the section, a lid having a main member 120 and an auxiliary overlying layer coextensive with said extension, a hinge mounted on the inner edge of the platform in connection with the lid at a portion transversely intermediate the ends thereof to close the container section, said lid 125 forming two superimposed parts one swingable away from the other on the hinge into horizontal position to project well beyond the same, and means on the lid and extension for keeping the lid over the container in closed relation. 130

3. In combination, an open casing having a weighted transverse rear wall with a raised platform thereon forming a rest, and a floor with marginal edges extending from the vertical and front walls of said casing, a two-piece foldable 135 lid section having its middle portion hingedly connected to said platform whereby part of the lid will extend across and away from said platform upon swingably opening said section, part of the lid section acting as a cover resting across 140 the casing, and interlocking means on the edges of the cover of the lid section and the extending marginal edges of the floor of the casing for retaining the lid section and the casing compactly together when the section is swung across the 145 top of the casing, said casing having a plurality of sub-compartments therein for pencils and the like.
